HOBBYHORSE

Minna R. Whitney, Upperville, Va.

Application June 21, 1949, Serial No. 100,503

4 Claims. (Cl. 272—1)

1

The present invention relates to hobby-horses for children and, particularly, to a type that may be applied to thigh and knee portions of the leg of a person, when in a sitting position, and jugged up and down by that person to simulate horse-back riding especially while a child is seated on the hobby-horse.

While a great variety of hobby-horses have been previously proposed, so far as applicant is aware, none has been provided for very small children, of an age capable of only sitting, and it has long been the practice of adults to "bounce" them on their "knee," while perhaps reciting nursery rhymes, such as "Banbury Cross," etc., to simulate horse-back riding—all this without the stimulus and excitement that is provided by a physical form representing a horse or other animal.

It is the broad object of the present invention to supply such stimulus and excitement for the child (and perhaps the adult) by the provision of a dummy comprising the head, neck and shoulder portions of an animal, the shoulder portion being rearwardly extended to provide a seat or straddle upon which the child may sit astride and having a longitudinal cavity at its underside to receive the knee and thigh of a seated person.

A further object of this invention is to provide a dummy of the character mentioned which is fashioned of a mass of soft yieldable material devoid of any rigid or hard elements in any portion of the figure (other than stirrups which may be of rubber and may be removable or which may be omitted), the body portion being rearwardly extended a sufficient distance beyond the withers of the dummy to provide a seat or straddle portion upon which a child may sit astride and the body portion having a longitudinal cavity on its underside and of sufficient depth to receive the knee and thigh of a seated person with the sides of said cushion mass embracing the sides of the knee and thigh of the person on which the dummy is placed, the sides extending deeply downwardly and being flexible so that when a child is seated on the dummy properly supported, the knees of the child will naturally press the said downwardly extending sides against the support and thus make a gripping engagement of the dummy against the support and prevent inadvertent or accidental slipping of the dummy on the support.

Other objects and features of the present invention will be apparent from the following specification and the accompanying drawings, in which latter like characters of reference refer to similar and like parts through the several views.

In the drawings, which illustrate the invention as it is now devised:

Figure 1 is a perspective view showing the improved hobby-horse of the present invention as

2

it may be applied in one position on the thigh and knee portion of a seated person and upon which a child may sit or ride;

Figure 2 is a rear end view of the hobby-horse shown in Fig. 1, but not applied to the leg of a person;

Figure 3 is a longitudinal sectional view taken substantially on line 3—3 of Fig. 2;

Figure 4 is a fragmentary detail view showing one manner of securing a tail to the rear of the toy and which may provide a handle to steady the toy and insure its being held in place on the knee;

Figure 5 illustrates a modification in the construction at the breast of the toy animal; and

Figures 6 and 7 illustrate different manners in which the hobby-horse of the invention may be used.

The form of the animal illustrated in the drawing has the characteristics of a horse, but it is within the purview and contemplation of this invention that the form of the dummy may be that of other animals; and the term "hobby-horse" is used merely as a convenience of expression for the dummy employed and not as a limiting term.

More specifically described, the invention employs an animal dummy, and comprising at least the head, neck and shoulder portions H, N and S, respectively, of the animal simulated, constructed of light-weight material, such as textile cloth, molded plastic material, sheet plastic or sheet rubber just to mention a few as examples. When made of air pervious sheet material a, which provides the outer contour surfaces, the dummy is stuffed with a suitable stuffing material s so as to give the dummy form and the necessary rigidity; but when the outer surface of the dummy is of an air-impermeable material a', such as plastic or rubber sheeting, the dummy may be given form and rigidity by inflating it with air, a suitable air-valve v (Fig. 6) being provided for this purpose. However, in all cases, the head H and neck N are to have sufficient rigidity with adjacent parts of the shoulder portion S as to be self-sustaining when in use, as shown, while the lower neck or breast portion b and the shoulder portion in the seat area are yieldably flexible, as will be pointed out. Of course, it is understood also that the dummy may be molded or otherwise fashioned into form or shape by the use of very light material now on the market, such as sponge or foam rubber and certain types of plastics, as examples.

In any event, the neck portion end of the dummy should include the upper portion of the breast b and the shoulder portion S is extended rearwardly of the neck portion N for a distance, as seen in the drawing, to complete the contour of the simulated animal so as to provide a seat 10 for the child to the rear of the head and neck portion. This seat 10 may take the form of a

saddle 11 and interposed between the saddle and the material *a* or *a'* may be the representation of a saddle cloth or pad 12. It is preferred that stirrups 13 hang from the seat or saddle in proper location. To this end, a stirrup strap 14 is interposed between the seat and saddle cloth, and has its ends hanging from each side of the dummy with its end portions looped through the stirrups 13 and may be adjustable through means of a buckle 15. The head of the dummy may be bridled, as at 16, with suitable reins 17 extending from the bit of the bridle to the seat portion 10.

As shown in Figure 2, the shoulder and neck portions are hollowed to form a deep cavity 18 on the underside of the dummy. This cavity extends longitudinally through the dummy from the rear of the seat 10 forwardly to the breast portion *b*, and is open at the underside and rear end of the dummy so that it may be conveniently placed over and about the knee and forward thigh portion of a person, when in seated position, as shown in Fig. 1. When so applied, as shown in Fig. 1, the breast portion *b* extends over and about the knee of the person, the walls of the breast portion acting as a stop and the sides of the shoulder portions and breast portion extending downwardly for a distance to envelope or embrace the knee and sides of the thigh (or other similar support as shown in Fig. 7) so that, when in use, the knees of a child sitting on the dummy will normally press said sides of the shoulder and breast portions against the object on which the dummy is supported and cause the dummy to grip the support from opposite sides and prevent inadvertent or accidental slipping of the dummy on the support.

The breast portion may be divided vertically, as particularly shown in Figs. 1, 2 and 3, by a slit 19 having its edges held in substantially closed position by an elastic means 20 which has its ends secured to opposite sides of the slit. The resiliency or elasticity of the elastic means 20 functions for the purpose of allowing the breast portion *b* to expand and tightly grip about the knee of the person upon which the dummy is applied.

In Fig. 5 is illustrated a modification of the resilient or elastic means 20, wherein it is made of two elastic strips 20a and 20b connected by discon-nectible and adjustable means 21 (such as a button and button-holes), thus enabling the user to adjust the breast portion *b* to more suitably fit the size of his or her knee or, when disconnected, to permit the dummy to be used in the position shown in Fig. 6 so that the child may face the person who is playing hobby-horse with him. This may be particularly desirable in the case of very young infants.

Secured to the rear of the shoulder portion *S*, at a point adjacent to the rear end of the seat 10, is a handle 22 which may be in the form of an animal's tail. This tail or handle portion 22 is securely stitched or riveted, or otherwise fastened by means generally indicated at 23, to the material forming the rear of the shoulder portion *S*. By grasping the handle or tail 22, the user of the dummy may pull the dummy backwardly so that the breast portion *b* will tightly fit against the knee and be retained in that position.

While this hobby-horse is particularly designed to insure the gripping of the knee or other object on which the dummy will be used, the walls of the cavity 18 may be provided with a layer 24 of sponge rubber or other roughened surface material such as velvet or the like.

As illustrated in Fig. 7, the use of the invention is not limited in connection with the knee or thigh of an individual and may be used as illustrated in Fig. 7 and in similar ways by older children during self-amusement.

Having thus described the invention and the manner in which it is to be performed, it is to be understood that the invention is not to be limited to the exact details of construction shown and described as the same may be varied materially within the scope of the appended claims.

That which is claimed as new is:

1. An animal dummy comprising a mass of material fashioned to simulate the head, neck and shoulder part of an animal, said mass consisting entirely of soft material, the head and neck portions at least being sufficiently rigid to be self-sustaining, the shoulder portion extending uninterruptedly for a distance rearwardly of the neck portion and forming a seat on its upper surface, the shoulder portion and the lower portion of the neck portion of said mass of soft material having a relatively deep longitudinal cavity on their underside, said cavity being open at its rear end and closed at its forward end and forming deeply downwardly extending yieldable front end and side portions extending the length of said dummy and adapted to fit over and around the thigh and knee of a person in sitting position or other similar support.

2. A dummy, as set forth in claim 1, wherein there is an opening extending upwardly from the lower edge of said neck at its front and a strip of resilient material connected to the material on opposite sides of the opening, whereby, when the masses of the material on opposite sides of the opening are spread apart as when the dummy is placed on the said support, said resilient material resiliently pulls and holds the material extending downwardly at the opposite sides of the neck portion into gripping and holding engagement against said support.

3. An animal dummy of the character described having head, neck, breast and shoulder portions having their surfaces merging and joined together and together simulating the head, neck, breast, opposite shoulders, opposite sides and back of an animal, such as a horse; the breast portion being a downward extension of the front of the neck portion and being bifurcated, the opposite shoulder portions joining and merging along the back of the dummy and extending rearwardly from the opposite sides of the neck and breast portions and being spaced apart, and a resilient tie joined to and pulling the bifurcated parts of the breast portion, and thereby the side portions, together and against opposite sides of an appropriate support straddled by said side portions, whereby the dummy is self-gripped to the support against sidewise rotational slipping thereon.

4. An animal dummy, as set forth in claim 3 composed entirely of a mass of soft flexible material self-sustaining in its shape.
